Primary Examiner — Philip S Hyder*Assistant Examiner* — Darlington Ly(74) *Attorney, Agent, or Firm* — Finnegan, Henderson, Farabow, Garrett & Dunner, LLP(57) **CLAIM**

The ornamental design for a fender flare, as shown and described.

DESCRIPTION

FIG. 1 is a front left perspective view showing our new design;

FIG. 2 is a front elevation view thereof;

FIG. 3 is a left side view thereof;

FIG. 4 is a rear elevation view thereof;

FIG. 5 is a top plan view thereof; and,

FIG. 6 is a bottom plan view thereof.

The claimed design includes a mirror image of the embodiment depicted.

The broken lines shown in the drawings illustrate portions of the fender flare that form no part of the claimed design. The side of the fender flare immediately adjacent to the truck body is not seen during ordinary use and is not part of the claimed design.
